Att'y.

UNITED STATES PATENT OFFICE.

GEORGE EASDALE, OF OTTAWA, ONTARIO, CANADA, ASSIGNOR OF ONE-HALF TO KETCHUM & COMPANY, OF OTTAWA, CANADA, A FIRM.

RECOIL-ABSORBER FOR FIREARMS.

No. 910,276.

Specification of Letters Patent.

Patented Jan. 19, 1909.

Application filed February 20, 1908. Serial No. 416,861.

To all whom it may concern:

Be it known that I, GEORGE EASDALE, of the city of Ottawa, in the county of Carleton, Province of Ontario, Canada, have invented certain new and useful Improvements in Recoil-Absorbers for Firearms, of which the following is a specification.

My invention relates to improvements in recoil absorbers for fire arms, and the objects of my invention are to provide improved means for spring cushioning the recoil of a fire-arm, such as a rifle or shot gun, working in combination with pneumatic means for affording an additional cushion and retarding the rebounding action of the spring.

Specifically considered in its relation to a rifle or shot gun, the invention includes an adjustable, pneumatically cushioned butt plate, and a grip plate also adjustable, and pneumatically cushioned, connected to the forward parts of the stock of the rifle or shot gun.

The invention is described in detail, in the accompanying specification and drawings.

In the drawings, Figure 1 is a side view of the rifle, partially in section having my improved recoil absorbing device attached thereto. Fig. 2 is an enlarged section through the side of the rifle. Fig. 3 is an enlarged longitudinal section through the grip plate on the forward part of the stock. Fig. 4 is an enlarged section through an alternative form of butt plate.

In the drawings, like letters of reference indicate corresponding parts in each figure.

Referring to the drawings, A represents the rifle of any suitable construction, a the stock thereof and b the butt.

In accordance with my invention, an adjustable butt plate B is provided, which, in the embodiment illustrated, is in the form of a shell having the sides c fitting over and slidably engaging the butt b. Centrally within the butt is a cylindrical recess d, within which tightly fits a tubular shell C, which has co-operative therewith, a slightly smaller shell D, the outer end of which is connected to the butt plate, through the medium of a connecting member E having a projection e thereon, with an interiorly screw-threaded recess r, which is engaged by a correspondingly exteriorly screw-threaded surface on the shell. Pneumatic resistance is provided both to the collapse

and distention of these shells, this being effected by a packing ring f, abutting the edge of the inner shell, and held in position there-against, by means of a flange h on a tubular member i having screw-threaded engagement with the interior of the shell D.

The shells are normally maintained in distended position by a compression spring F located within the same, and the pneumatic action is further increased by means of two additional co-operating shells G and H, which fit, air-tight, one within the other, the outer shell G having the end abutting the projection e and the inner shell H having screw-threaded engagement with an internally-screw-threaded recess k in a plug j which forms the inner end of the shell C and which may be retained in position by a transverse pin n.

It will be observed that on the recoil of the rifle and when the parts of the apparatus are collapsed, a pneumatic cushion will be provided both between the shells C and D and between the shells G and H, and after the recoil, the butt plate will be moved gradually back to its normal position under the action of the spring F, which spring has also afforded resistance to the inward movement. The result of this arrangement is to provide an exceedingly uniform movement of the butt plate, doing away with the rapid recoil produced by spring action alone, which is exceedingly disadvantageous. In the present case, the connection between the tubular members are only practically and not absolutely air-tight, so that a certain amount of air will be forced out during the collapsing and this will prevent the spring moving the butt plate back too rapidly, as the air forced out must be drawn in gradually around the joints.

The cushioned grip plate on the forward part of the stock is substantially the same in construction, as that in the butt, and consists of two tubular shells I and J, fitting air-tight, one within the other, and normally extended by a spring K, second shells L and M extending about these, fitting one within the other, and provided with an air-tight connection by means of the packing ring q, held in position by the flange p on the tube l which has screw-threaded engagement with the interior of the shell M.

The shell M is connected to the rifle by means of a suitable strap m, while the shell

L is adapted to serve as a grip plate for the rifle-man, the end being closed by a screw-threaded plug N, which has an internally-screw-threaded recess o therein, into which the shell I fits. When the combination of the grip plate and butt plate is employed, the recoil of the rifle will scarcely be felt by the rifleman, and the course of the shooting will thus be correspondingly more accurate.

10 In the form shown in Fig. 4, an outlet passage s is provided in the connecting member F, the said passage having a valve seat t provided therein, with a ball check valve u seated thereon. In this form, the recoil of the rifle is practically entirely absorbed by the spring, the air flowing freely out through the check valve, while the return movement will be deadened by the pneumatic cushion and the undesirable kick of the spring eliminated.

It will be evident that the invention may be applied to absorb the recoil of practically any part of a fire arm, and changes within the scope of the appended claims may be made, without departing from the spirit of the invention.

What I claim as my invention is:—

1. In a rifle or shot gun, the combination with the butt of a reciprocative butt plate, spring means for normally retaining the same in outermost position, of collapsible co-acting air-retaining members connected respectively to the butt and to the butt plate and adapted to permit the air to only gradually flow in and out during their collapse and distention, whereby a pneumatic cushion will be provided to the movement of the butt plate both ways.
2. In a rifle or shot gun, the combination with the butt and reciprocative butt plate, of two co-acting telescopic shells connected respectively to the butt and the butt plate and fitting closely to each other, and adapted to permit the air to only gradually flow in and out, whereby a pneumatic resistance will be provided to both the collapse and distention, and a spring within the shells normally distending the same.

3. The combination with a fire arm and reciprocative movable member thereof, of a recoil absorber, including two concentric shells connected to the firearm, two similar concentric shells connected to the movable part, each of the shells having a practically air-tight connection with the corresponding shell of the opposite pair and a spring inclosed within the pairs of the shells normally extending the same.

4. The combination with a fire-arm and reciprocative, movable part thereon, of a recoil absorber, including a tubular shell connected to the fire-arm, a like tubular shell fitting the same and connected to the movable part, a packing ring between the two shells, and a tubular member having screw-threaded engagement with the inner shell and also having a flange adapted to tighten the packing ring.

5. In a fire arm, a recoil absorber including two tubular shells fitting air-tight, one within the other, one of said shells being provided with an outlet passage-way, of a check valve in the outlet passage-way adapted to permit the egress but prevent the ingress of air, and a spring within the members normally distending the same.

6. In a fire-arm, the combination of a reciprocative cushioning butt plate with a reciprocative grip plate on the forward part of the stock, and means for cushioning the movement of the grip plate.

7. In a fire-arm, the combination with a reciprocative butt plate, spring means for returning it to normal position when moved therefrom, and pneumatic means for retarding the movement thereof, of a reciprocative grip plate on the forward part of the stock and means for offering a spring and pneumatic resistance to the movement of the same.

In witness whereof I have hereunto set my hand in the presence of two witnesses.

GEORGE EASDALE.
